UNITED STATES PATENT OFFICE.

JOHN W. NILSSON, OF BALFOUR, NORTH DAKOTA.

HORSE-PROTECTOR.

1,159,076.

Specification of Letters Patent.

Patented Nov. 2, 1915.

Application filed October 10, 1914. Serial No. 866,118.

To all whom it may concern:

Be it known that I, JOHN W. NILSSON, a citizen of the United States, residing at Balfour, in the county of McHenry and State of North Dakota, have invented certain new and useful Improvements in Horse-Protectors, of which the following is a specification.

This invention relates to horse protectors, and is an improvement on the protector which is the subject of my Patent Number 1,113,815, granted October 13, 1914.

One of the principal objects of the invention is to provide an improved device for protecting a horse's head from attacks from bot-flies and other insects, consisting of a flexible strip of material suspended from a rigid frame and maintained in place thereon partially by a pair of clips, the latter serving as means for securing the protector to a bridle.

A further object of the invention is to provide a protector of the type set forth, in which simplicity of structure and economy of manufacture is coupled with durability and efficiency in operation.

With these and other objects in view which will become apparent as the description proceeds, the invention resides in the construction, combination and arrangement of parts, hereinafter more fully described and claimed, and illustrated in the accompanying drawing, in which like characters of reference indicate like parts throughout the several figures, of which—

Figure 1 represents a perspective view of an improved protector constructed according to my invention, and Fig. 2 represents a vertical transverse sectional view of the device taken centrally therethrough.

In carrying out my invention I provide a strip of textile material indicated at 5, which is preferably rectangular in shape, and which is folded over at its ends as at 6 to form a loop. The ends of the material are overlaid with tape as at 7 and are stitched to the body of the strip. The longitudinal edges 8 of the strip of material may be hemmed and provided with tape as indicated at 9.

A rigid framework 17 is provided which is substantially rectangular in formation and may consist of a length of wire 18 bent to form, and upon whose longitudinal members the loops at the ends of the textile material are strung in the manner indicated in

the drawing. The transverse members 10 of the frame extend laterally of the protector as shown and are preferably covered with a suitable cloth. The width of the frame is somewhat less than the length of the strip of textile material, so that the latter when in position depends or hangs from the frame and is substantially U-shaped in cross section.

The clips indicated at 11 are each formed of a length of wire bent to form a central loop 12. Inner arms 13 in the form of loops are disposed on each side of central loop 12 and extending in an opposite direction therefrom, the ends of the length of wire being twisted to lie in planes at right angles to the planes of the loops 13 and in spaced relation therefrom so as to form bridges or saddles 14 which engage over the loop portions 6 of the textile material and as indicated in Fig. 2 are crimped against the outer surfaces thereof as at 16 whereby the loops 6 are clamped upon the longitudinal bars of the frame. The loops 12 project above the framework and serve as means through which suitable straps of a bridle (not shown) may be passed for connecting the protector to the bridle. When in position the protector depends below the animal's mouth and extends from one side to the other thereof.

The particular advantage of the frame lies in the fact that by its use the ends of the textile material or those portions thereof lying nearest the horse's mouth may be braced in position so that they may not be oscillated with the loops as a center by action of the wind or from any other cause, so that the horse or other animal to whose bridle the protector is fastened will not be annoyed by swaying or relative movement of the adjacent portions of the protector.

Although I have described the preferred embodiment of my invention, I may desire to make such changes in the construction, combination and arrangement of parts thereof as do not depart from the spirit of the invention and the scope of the appended claims.

I claim:—

1. A protector comprising a strip of textile material folded upon itself at its ends to form loops, a rigid frame over which said loops are strung for connecting said strip to the frame, and clips engaging upon the center portions of the loops and clamping them against the frame, the said clips in-

- cluding upwardly extending loops adapted to be engaged by suitable straps of a bridle, for swingingly suspending the protector below an animal's mouth.
5. A protector comprising a strip of material, a substantially rectangular frame, means for connecting the strip to the longitudinal members of the frame, and means for clamping said strip to the longitudinal members centrally thereof, the last said means adapted to be swingingly connected to a bridle for suspending the protector below an animal's mouth.
10. A protector comprising a substantially rectangular strip of flexible material, means for swingingly suspending the strip transversely beneath an animal's mouth, a frame partially housed by the strip for bracing the ends of the strip against movement rela-
15. 3. A protector comprising a substantially

tively to each other, and covering means for the exposed portions of the frame.

4. In a protector, the combination with a flexible substantially rectangular strip of material adapted to be swingingly suspended transversely beneath an animal's mouth in such manner as not to engage the latter and to leave the mouth unobstructed at front and rear, of a rigid substantially rectangular frame secured to the strip to maintain the ends of the same against movement relatively to each other, said frame adapted to encompass the animal's mouth in spaced relation thereto.

JOHN W. NILSSON.
